DOOR MORTISING MACHINE

Filed Dec. 2, 1925

2 Sheets-Sheet 2

UNITED STATES PATENT OFFICE.

RAY L. CARTER, OF PHOENIX, NEW YORK.

DOOR-MORTISING MACHINE.

Application filed December 2, 1925. Serial No. 72,722.

This invention relates to improvements in portable mortising machines, designed especially for preparing doors for the reception of the well-known mortise locks.

5 The invention relates particularly to improvements in the mortising devices shown and described in my pending application filed April 8, 1925, Serial No. 21,601.

The object of the present invention is to 10 provide a hand-controlled power driven mortising and routing device, in which the tool is operated by an electric motor, the motor and tool being oscillated manually in planes to suit the lay of the work. A further 15 object is to provide a novel adjustable bracket that supports the mortising mechanism and may be readily and quickly clamped to the edge of a door or other part. A further object is to provide a novel shoe, 20 which directly and pivotally supports the motor and its housing, the said shoe being slidably measured distances upon an arm of the bracket for progressively sinking, as well as for withdrawing the tool from a 25 mortise. A further object is to provide novel means for automatically jogging the motor and tool towards the work at each stroke of the operating handle during the mortising operations. A further object is to 30 provide novel and simple means for gaging the oscillations of the tool and motor for varying one dimension of the mortises. And a further object is to generally improve and simplify the construction, arrangement and 35 operation of mortising machines of this class.

The various features and parts of the invention will be understood from the detailed description which follows, and by reference 40 to the accompanying drawings, in which—

Figure 1 is a front side elevation of the complete device mounted upon a door or like part, in the act of sinking a mortise. Fig. 2 is a bottom side view of the same. Fig. 3 is a top side view of the device. Fig. 4 is a 45 rear side elevation, in which the full lines show the bracket, the shoe, and the jogging mechanism, as when the handle is depressed; the dotted lines showing the motor and tool, and also the jogging parts operated by the 50 lifting of the handle. Fig. 5 is a horizontal section, taken on line 6—6 of Fig. 2. Fig. 6 is a similar section, taken on line 6—6 of Fig. 2. Fig. 7 is a rear-end elevation of the 55 complete machine. Fig. 8 is a side elevation of the motor and holder, and Fig. 9 is a rear-end elevation of the same.

In the drawings, the motor 2 is enclosed by the usual cylindrical casing 2'. 2^a represents the armature shaft, which extends beyond the front end of the motor and supports and drives the tool 3 and its tubular shank 3'. The encased motor is supported by a hollow holder 4, whose leg 4^x is pivotally mounted upon a pin or post 4', the said leg being split, as at 4^a, and being provided with a bolt 4^b, by which the holder may be adjustably clamped to the post. The motor and its holder are rotatably supported by a shoe 5, as best seen in Figs. 2, 3, 5 and 6; the shoe being slidably mounted upon a guide-arm 6 of a bracket 6', and the lateral edges of said arm being formed with V-shaped grooves 6^a, which are engaged respectively by a tongue 5', and by the conical end of a set-screw 5^a carried by the shoe, as best seen in Fig. 7. The bracket 6' comprises a body 6^c, whose opposite ends are formed with similar hollow legs 6^d, which pivotally support differential screws 7—7', 60 the top ends of said screws being fitted with hand-knobs. The screws 7—7' each control a pair of clamping members, as 7^b—7^c, the said members being formed with threaded hubs or bosses 7^d that receive the corresponding screws; the members 7^b being adapted to move towards or away from the members 7^c by the rotation of the screws 7—7', as indicated by the directions of the threads (see 65 Figs. 2, 3 and 7). The legs 6^d, and also the corresponding members 7^b—7^c, are formed with aligning perforated lugs 7^e, which support similar guide-rods 8, the latter paralleling the screws 7—7' and having their lower ends anchored in the legs 6^d. By this 70 construction and arrangement, the members 7^b—7^c register with each other, and the bracket may be readily, quickly and rigidly clamped to doors or other work of different 75 thicknesses. A represents a fragment of a door, in which a partially wrought mortise is shown. The shaft 2^a, between the motor and the tool 3, is preferably supported by a relatively long tubular shank 2^c, one end of which is knurled and secured to the motor casing by any suitable means (not shown). The motor and tool may be oscillated or 80 rocked in the plane of the door A, as shown in Figs. 1, 4, 5 and 6, by means of a handle 9, which is detachably supported by a threaded 85

55 100 105 110

boss 4^c formed at one side of the holder 4. During the mortising, the handle 9 is operated like a pump-handle. The rocking movements of the motor and tool are regulated by a pair of blocks or nuts 10, which are adjustably mounted upon a differential screw 10', the said blocks being square for convenience and contacting with the shoe 5, for preventing their rotation, and being movable towards and away from each other simultaneously, for decreasing and increasing their spacings, by the turning of a knurled knob 10^a, which is mounted upon one end of the screw 10'. The screw 10' is supported by perforated lugs 5^b, which rise from the outer surface of the shoe. The blocks 10 gage the oscillations of a finger or stud 4^d, which is supported by the holder 4, as best seen in Figs. 3, 5 and 6.

20 The motor and tool, and also the shoe are jogged or moved towards the work (A), by means of a ratchet-rack 12, which is rigidly secured to the rear face of the guide 6, and a pair of oppositely facing toothed dogs or pawls 12^b—12^a, the latter being pivoted by bolts 12^b, to a flattened collar or sleeve 13 that loosely surrounds the guide 6 and the shoe 5. The sleeve 13 is preferably pivoted to the shoe by a bolt 13', and is rockable in one direction in the plane of the door and guide 6, as shown in Figs. 4, 5 and 6, by means of a roller 14, which is pivoted in the leg 4^x of the holder (see Figs. 5, 6, 8 and 9), and engages a cam 14' which is mounted upon the sleeve 13, as best seen in Figs. 5, 6 and 7. Sleeve 13 is operated in the opposite direction by a piston or bolt 15, which is reciprocatable in a socket formed in a boss 5^d of the shoe, the said piston being extended (see Figs. 1, 3, 4 and 6) by a spring 15', as shown in Fig. 6. According to this novel arrangement of the said parts, when the handle 9 is depressed, as shown in Fig. 5, the roller 14 moves over the angular face 14^a of the cam (see Fig. 5), and rocks the sleeve 13 on the pivot 13', in the direction for forcing the piston 15 into the socket. This moves the dog 12^a forwardly along the rack 12 the extent of one tooth; and while the dog 12^a is thus being advanced, the dog 12^b holds fast to the rack and causes the shoe, the motor and the tool, to be correspondingly advanced towards the mortising position. The lifting of the handle 9, moves the roller 14 back into the bight of the cam, shown at 14^b in Fig. 6, and allows the tension of spring 15' to swing the sleeve 13 in the opposite direction (as shown in Fig. 6), which effects the advance of the pawl 12^a, while the pawl 12^b holds fast. At each rocking of the sleeve 13 by the swinging of the handle 9, the pawls 12^b—12^a are alternately jogged forwardly tooth by tooth, along the rack 12. This correspondingly moves the tool 3 for deepen-

ing the mortise, as explained. Owing to the peculiar shape of the cam 14' the advance of the motor at the start of each rocking movement of the handle is almost imperceptible, and the initial cutting by the tool is so slight, that danger of stalling the tool is obviated. However, as the handle continues its swing, the roller 14 engages the angular face 14^a of the cam, which rocks the lower end of the sleeve 13 rearwardly, as indicated in Fig. 6 and effects the gradual advance, and increases the depth of the cutting by the tool to the end of the stroke, as shown by the dotted lines α in Fig. 4. This provision enables the machine to effect uniform work, and permits the handle 9 to be operated rapidly without danger of jamming the tool or distorting the mortise.

The depth of the mortises may be accurately gaged, by means of a pin 16, which is arranged to be set in any one of a number of holes 16', which are formed in the guide-arm 6 (see Figs. 2 and 4). To accomplish this, the dog 12^a is formed with an angular arm 12^c (see Fig. 4), which is disposed in the path of the pin, and as the dog approaches the pin, it is deflected laterally sufficiently to unmesh the tooth portion of the dog from the rack 12. This stops the forward jogging of the shoe and motor and terminates the mortising operation.

The improved means for effecting the clamping of the device to a door or like part, the novel and simple means for gaging the oscillations of the motor and tool, and the extremely simple and effective cam action, by which the sleeve 13 is rocked in one direction, for jogging the tool towards the work and the reverse movement of the sleeve being effected by the tension-controlled member 15, greatly reduces the number of working parts, and facilitates the ready and accurate adjustment and operation of the machine.

Having thus described my invention, what I claim is—

1. In a mortising machine, a motor, a holder for the motor, a tool driven by the motor, a handle for oscillating the motor and tool, a roller carried by the holder, and a sleeve having a cam portion in constant engagement with the roller, said cam portion being arranged to effect variable forward movements of the tool during each oscillation of the motor.

2. In a door mortising machine, a motor, a holder for the motor, a tool driven by the motor said tool and said motor adapted to be oscillated manually, a roller carried by the holder, and a sleeve having a cam portion in constant engagement with said roller adapted to be rocked by the roller for effecting a graduated cutting by said tool.

3. In a door mortising machine, an enclosed motor, a tool driven by the motor

adapted to be oscillated manually by a handle carried by the motor casing, a slidable shoe upon which the motor is pivoted, a roller carried by the motor casing, and a 5 sleeve pivoted to the shoe and rocked by said roller for effecting the forward movement of the motor and tool during the mortising operations.

4. In a mortising machine, a bracket having a guide-arm, a shoe slidable on said arm, an encased motor pivoted on the shoe adapted to be oscillated by a hand-lever, a tool driven by the motor, a jogging mechanism supported jointly by said arm and said shoe, 10 a rockable sleeve for actuating the jogging mechanism said sleeve having a cam portion, and a member carried by the motor casing in constant engagement with the cam portion of said sleeve adapted to effect the movement 15 of the sleeve at variable speeds during each oscillation of the motor, and means for oscillating the motor and tool.

5. A mortising machine including a bracket having a guide-arm, a shoe slidable 25 on said arm, an encased motor pivoted on the shoe adapted to be jogged towards the work by its oscillations, a tool driven by the motor, a mechanism for jogging the motor and tool comprising a rack and a pair of dogs, a rockable sleeve for actuating the jogging mechanism, a member carried by the motor casing in constant engagement with 30 said sleeve adapted to effect the movement of the sleeve at variable speeds during each oscillation of the motor, means for oscillating the motor and tool, and means for gaging the oscillations of the motor for varying one dimension of the mortise.

6. In a mortising machine, an enclosed oscillatable motor, a tool driven by the motor, a handle for rocking the motor and tool in opposite directions during the sinking of a mortise, a screw adapted for gaging the extent of the rocking movements of the motor, 45 a roller adapted to effect the jogging of the tool towards the work when the handle is swung in one direction, and tension controlled means for jogging the tool towards the work while the handle is being swung in 50 the opposite direction.

7. A mortising machine, including an encased motor, a tool driven by the motor, a support for the motor, a pair of screws for

adjustably clamping the support to the work, means for oscillating the motor for effecting 55 the measured jogging of the motor and tool towards the mortising position, means for gaging the oscillations of the motor for varying one dimension of the mortise, a cam mechanism for jogging the tool while the 60 motor is being oscillated in one direction, tension-controlled means for jogging the tool while the motor is being oscillated in the opposite direction, and means for increasing the depth of the cutting by the tool 65 during each oscillatory movement of the motor.

8. In a mortising machine, a bracket adapted to be clamped to a door or other part having a guide arm provided with lateral 70 grooves, a shoe slidable on said guide arm and having tongues that engage said grooves, an encased motor pivoted to said shoe and supporting and driving a mortising tool, a finger movable with the motor casing, a 75 screw mounted on the shoe, gage-blocks threaded to said screw between which said finger plays adapted to be moved towards and from each other for varying the sweep of said finger, means for oscillating said motor during the mortising operations, means for jogging the motor and tool towards the mortising position, and means comprising a cam and a tension controlled device for alternately effecting the jogging work. 85

9. In a door mortising device, the combination with a bracket adapted to be clamped to a door and having a guide arm formed with lateral grooves extending away from the door, of a member slidable on said arm 90 having parts that play in said grooves, a rack carried by said arm, a sleeve pivoted to said member, a pair of dogs supported by said sleeve having teeth engaging said rack 95 adapted to alternately jog said member towards the door by the rocking of said sleeve, a motor supported by a holder pivoted on said member, a tool driven by the motor, a roller carried by said holder adapted to rock the sleeve in one direction, means carried by 100 said member for rocking the sleeve in the opposite direction, and means for oscillating the motor and tool.

In testimony whereof I affix my signature.

RAY L. CARTER.
